UNITED STATES PATENT OFFICE.

RAYMOND G. MOORE, OF BRIDGEPORT, CONNECTICUT, ASSIGNOR TO THE BASSICK COMPANY, OF BRIDGEPORT, CONNECTICUT, A CORPORATION OF CONNECTICUT.

AUTOMOBILE DOOR LATCH.

Application filed May 23, 1924. Serial No. 715,272.

To all whom it may concern:

Be it known that I, RAYMOND G. MOORE, a citizen of the United States, and a resident of Bridgeport, in the county of Fairfield and State of Connecticut, have invented certain new and useful Improvements in Automobile Door Latches, of which the following is a specification.

This invention relates to improvements in 10 automobile door latches, and has for an object to provide a latch of this character, having both an inside and an outside operating handle, and which may be locked from the inside, so as to prevent operation 15 of the outside handle. This type of latch is especially adapted for use upon doors of closed cars, one of the doors of which is adapted to be locked from the outside, while the others, provided with latches according 20 to the present invention, are locked from the inside.

A further object is to provide a latch in which the locking means is incorporated in the inside handle structure, in such manner as to be attached to the inside handle lever, without necessitating any change or alteration in the operative parts of the latch proper.

A still further object is to provide a latch 30 having a double acting outside handle, which will be locked against movement in either direction upon operation of the improved locking means, and also to provide an inside locking handle adapted to be 35 moved to locking position by merely moving the same in a direction opposed to the usual swinging movement employed in retracting the latch, and to be unlocked simply by moving the handle in the usual manner to 40 retract the latch.

Other objects are to provide a locking handle structure enabling the use of a relatively short inside retracting lever, thereby simplifying and economizing the manufacture and assembly, and to provide locking means which will not readily get out of order.

With the above and other objects in view, 50 embodiments of the invention are shown in the accompanying drawings, and these embodiments will be hereinafter more fully described with reference thereto, and the invention will be finally pointed out in the claims.

In the drawings:

Fig. 1 is an inside elevation of the corner of an automobile door provided with one embodiment of the invention, and showing in dotted lines the retraction position of the inside and outside handles; 60

Fig. 2 is a similar view, and showing the inside handle in locked position;

Fig. 3 is an enlarged detail view, in elevation, of the locking means, and showing the same in unlocked position; 65

Fig. 4 is a similar view, partly in section, and showing the locking means in locked position;

Fig. 5 is a horizontal sectional view, taken along the line 5—5 of Fig. 3; 70

Fig. 6 is an inside elevation of the corner of an automobile door provided with a modified form of the invention, the inside handle being shown in unlocked position;

Fig. 7 is a similar view, and showing the 75 inside handle in locked position;

Fig. 8 is an enlarged detail view, in elevation, of the locking means, and showing the same in unlocked position;

Fig. 9 is a similar view, partly in section, 80 and showing the locking means in locked position;

Fig. 10 is a horizontal sectional view, taken along the line 10—10 of Fig. 8; and

Fig. 11 is a detail view in elevation, of 85 a further modified form, and showing the same in unlocked position.

Referring to the drawings, and more particularly to Figs. 1 to 5 thereof, the embodiment of the invention shown therein 90 comprises a latch 10 secured to the automobile door 11 in the usual manner, and including a rectilinearly movable bolt 12 slideable in a guide-way 13, and normally projected by means of a coil spring 14, being 95 provided with a cut-out 15 in which is engaged the inside handle lever 16, pivoted upon the latch frame at 17, and normally pressed forwardly, as shown in full lines Fig. 1, by means of a spring 18. 100

The outside handle 19 has its squared shank 20 engaged in a rotatable roll-back 21, having a heart-shaped cam 22 engaging above and below a hump-shaped cam portion 23 of the lever 16. By swinging the lever 16 rearwardly the bolt will be retracted, or the same may be retracted by turning the outside handle 19 in either direction, this latter operation swinging the lever 16 and thereby effecting retraction of 110

the bolt, as indicated in dotted lines Fig. 1. By locking the lever 16 against retracting movement the outside handle will be positively locked, and the present invention 5 consists in the provision of means for locking said lever from the inside of the car.

The handle for the lever 16 consists of an extension portion or hand-grip 24 extending through a slotted escutcheon 25 in the upper 10 sill of the door, and screwed upon an interior arm portion 26, the latter being angularly bent intermediate its vertically disposed ends. At its lower end the arm is adapted to be pivotally secured to the upper 15 end of the lever 16 for relative swinging movement in one direction, and for this purpose the extremity of said lower end of the arm is cut at an angle, preferably forty-five degrees, as at 27, and has a coupling member 28 of U-shape in horizontal cross-section engaged about said end and rigidly secured thereto by rivets 29, said coupling member extending below said inclined extremity and embracing the upper end of the lever 16, to 25 which it is pivotally secured by a rivet headed pin 30. The upper extremity of the lever 16 is extended slightly above the latch casing and is cut angularly, as at 31, to be solidly engaged by the angular extremity 27 30 of the arm in the vertically aligned position of the same with the lever, so that upon swinging movement of the handle to retracting position, as indicated in dotted lines Fig. 1, the handle arm and lever move as a rigid 35 unit. The handle arm is adapted, however, to have limited relative swinging movement in the direction opposed to the retracting movement, and to this end the forward portion of the inclined extremity 31 is rounded off, as at 33, and the forward wall of the coupling member is cut away below the forward end of the inclined extremity 27, as at 34.

The coupling member is provided in continuation of its inner wall with a rearwardly and downwardly extending arm portion 35, bent as at 36 in spaced relation to the vertical edge of the lever 16 and arm 26 into adjacent and parallel relation with the inner side of the latch casing. At the end of the arm 35 there is provided a shouldered stud 37, riveted therein, and engaging a slot 38 in the latch casing formed concentric with the pivotal axis of the lever 16, the stud being headed, as at 39, at the forward side of the casing. The slot 38 is provided at its forward end with an upwardly extending cut-out 40 of substantially circular conformation to receive the stud 37, and disposed concentrically to the axis of the pin 30. The forward wall of the slot is provided with a rounded projection 41, over which the stud is adapted to be forced as it is moved from one position to the other, 65 while the opposed wall of the cut-out 40 is

undershot, as at 42, to form a locking shoulder.

The upper edge of the latch casing is cut away at 43 to allow for swinging movement of the lever, with the coupling member thereon, the lower end of said member extending into said portion 43.

The operation is as follows:

In the normal position of the handle, Figs. 1 and 3, the relatively long bearing surfaces 75 formed by the inclined extremities 27 and 31 are in solid contact with each other, and the handle and lever are adapted to be swung as a rigid unit to retracting position, the stud 37 moving from one end of the slot 38 to the other, as clearly shown in Fig. 1; the latch being also operable by means of the outside handle in this unlocked relation of the inside lever handle.

In order to lock the handle, the same is 80 merely swung forwardly from its normal position to the position indicated in Fig. 2, the stud 37 moving into the cut-out 40, it being necessary in moving the handle to such position to overcome the slight friction of the 85 projection 41, and which normally serves to prevent accidental movement of the handle to locking position, or to unlocked position when the same is locked. In this locked position the lever 16 is held against swinging 90 movement as applied thereto through operation of the outside handle, and the latch is therefore effectively locked against operation by the outside handle. The latch is unlocked simply by moving the inside handle 95 in retracting direction, the initial movement disengaging the stud from the cut-out 40.

In Figs. 6 to 10 I have illustrated a modified form of the invention, the latch structure being substantially the same as the first 100 described form. The handle arm 44 in this embodiment is bent at an angle at its lower half in line with the angularly cut end 31 of the lever 16, so that its lower edge solidly 105 engages said end, said arm being provided at its lower end with a U-shaped coupling member 45, secured thereto by rivets 46, and projecting at each side into embracing relation with the end of the lever 16, being pivotally connected to the lever by a rivet-headed pin 47. The handle arm is thus 110 adapted to swing rigidly with the lever in retracting direction, and to be swung relatively to said lever upon movement in the 115 other direction.

The end of the arm 44 extends below the coupling member and has a tooth 48 formed thereon, and off-set by bending, as at 49, into superimposed relation with the upper edge 120 of the latch casing. In the unlocked position, Figs. 6 and 8, the lower edge of the tooth is above the upper edge of the latch casing and free to be swung in retracting direction. In order to lock the lever, the handle is swung forwardly, to the position 125

indicated in Figs. 7 and 9, whereupon the tooth 48 is engaged in a cut-out 50 in the upper edge of the casing, the inner edge of the tooth being inclined or undershot, as at 51, and the inner wall of the cut-out being also inclined, so that the same are interlockingly engaged, thereby locking the lever against swinging movement, through turning the outside handle, and consequently preventing operation of said outside handle.

The latch is unlocked simply by moving the handle in retraction direction, the initial movement disengaging the tooth 48 from the cut-out 50.

15 The upper edge of the latch casing is cut away, as at 52, to allow for swinging of the lever, with the coupling member thereon, the lower end of said member extending into said portion 52.

20 In Fig. 11 there is illustrated a further modified form, substantially similar in construction and operation to the first form, but in which, instead of the stud 37, the end of the arm 35 is bent into the form of a 25 relatively flat elongated lug 53, engaging the slot 38 and adapted in the locked position of the handle to be moved into an elongated cut-out 54 in the forward end of the slot. With this construction the handle may 30 be moved to locked and unlocked positions with a relatively short swinging movement. In this form there is also illustrated a spring 35 detent for yieldably retaining the handle in either its locked or unlocked position, the function of such spring means being substantially the same as that of the projection 40 41 in the form illustrated in Figs. 1 to 5. This spring detent comprises a leaf spring 45 pivoted upon the latch casing as 56, and provided at one end with a V-shaped cut-out 57 engaging the lug 53, while at its 50 other end it is formed into V-shaped cross-section, as at 58, and is engaged at either side by a struck-up boss 59 of the casing, 55 the action between the spring and boss being to swing the former in either direction with a snap movement. Lugs 60 and 61 on the casing limit the movement of the spring in either direction. It will be understood 60 that a spring detent substantially similar to this may be used in the other embodiments of the invention.

I have illustrated and described preferred and satisfactory embodiments of the invention, but it will be obvious that changes may be made therein, within the spirit and scope thereof, as defined in the appended claims.

Having thus described my invention, what I claim and desire to secure by Letters

65 Patent is:

1. In a latch, a bolt adapted to be projected and retracted, inside bolt retracting means, a handle for said inside bolt retracting means pivoted thereto for relative pivotal movement in one direction, means

adapted to cooperate with said handle to lock said retracting means upon said relative pivotal movement of said handle, and outside bolt retracting means adapted to be locked against operation through the locking of said first retracting means.

2. In a latch, a bolt adapted to be projected and retracted, inside bolt retracting means, a handle for said inside bolt retracting means connected thereto for relative movement in a direction opposed to the retraction movement of said means, means adapted to cooperate with said handle to lock said retracting means upon said relative movement of said handle, and outside bolt 75 retracting means adapted to be locked against operation through the locking of said first retracting means.

3. In a latch, a bolt adapted to be projected and retracted, inside bolt retracting means, a handle for said inside bolt retracting means connected thereto for relative movement in a direction opposed to the retraction movement of said means, means adapted to cooperate with said handle to lock said retracting means upon said relative movement of said handle, and to unlock said handle upon movement thereof in retraction direction, and outside bolt 80 retracting means adapted to be locked against operation through the locking of said first retracting means.

4. In a latch, a bolt adapted to be projected and retracted, inside bolt retracting means, a handle for said inside bolt retracting means connected thereto for relative movement in a direction opposed to the retraction movement of said means, means adapted to cooperate with said handle to lock said retracting means upon said relative movement of said handle, the initial movement of said handle in retraction direction adapted to unlock said retracting means, and outside bolt retracting means adapted to be locked against operation through the locking of said first 95 retracting means.

5. In a latch including a casing, a bolt adapted to be projected and retracted, inside bolt retracting means, a handle for said inside retracting means pivoted thereto adjacent said casing for relative pivotal movement in one direction, means adapted to cooperate with said handle to lock said retracting means upon said relative pivotal movement of said handle, and outside bolt retraction means adapted to be locked against operation through the locking of said first 110 retracting means.

6. In a latch including a casing, a bolt adapted to be projected and retracted, inside bolt retracting means, a handle for said inside bolt retracting means pivoted thereto for relative pivotal movement in one direction, means on said latch casing adapted to cooperate with said handle to lock 125

- 5 said retracting means upon said relative pivotal movement of said handle, and outside bolt retracting means adapted to be locked against operation through the locking of said first retracting means.
10. In a latch, a bolt adapted to be projected and retracted, inside bolt retracting means having an inclined extremity, a handle for said inside bolt retracting means, including an inclined surface adapted to engage said inclined extremity, and pivotally connected to said retracting means for relative pivotal movement in one direction, means adapted to cooperate with said handle to lock said retracting means upon said relative pivotal movement of said handle, and outside bolt retracting means adapted to be locked against operation through the locking of said first retracting means. 45
15. In a latch including a casing, a bolt adapted to be projected and retracted, an inside bolt retracting lever pivoted thereto for relative pivotal movement in one direction, means adapted to cooperate with said handle to lock said retracting means upon said relative pivotal movement of said handle, and outside bolt retracting means adapted to be locked against operation through the locking of said first retracting means. 50
20. In a latch including a casing, a bolt adapted to be projected and retracted, an inside bolt retracting lever pivoted to the latch casing and terminating adjacent the edge of said casing, an extension handle arm pivoted to the end of said lever for relative pivotal movement in one direction, means adapted to cooperate with said handle arm to lock said retracting means upon said relative pivotal movement of said handle arm, and outside bolt retracting means adapted to be locked against operation through the locking of said first retracting means. 55
25. In a latch, a bolt adapted to be projected and retracted, inside bolt retracting means, a handle for said inside bolt retracting means, a coupling member pivotally connecting said handle to said retracting means for relative pivotal movement in one direction, means adapted to cooperate with said handle to lock said retracting means upon said relative pivotal movement of said handle, and outside bolt retracting means adapted to be locked against operation through the locking of said first retracting means. 60
30. In a latch, a bolt adapted to be projected and retracted, inside bolt retracting means, a handle for said inside bolt retracting means, a coupling member pivotally connecting said handle to said retracting means for relative pivotal movement in one direction, means adapted to cooperate with said handle to lock said retracting means upon said relative pivotal movement of said handle, and outside bolt retracting means adapted to be locked against operation through the locking of said first retracting means. 65
35. In a latch, a bolt adapted to be projected and retracted, inside bolt retracting means, a handle for said inside bolt retracting means, a coupling member pivotally connecting said handle to said retracting means for relative pivotal movement in one direction, means adapted to cooperate with said handle to lock said retracting means upon said relative pivotal movement of said handle, and outside bolt retracting means adapted to be locked against operation through the locking of said first retracting means. 70
40. In a latch, a bolt adapted to be projected and retracted, inside bolt retracting means, a handle for said inside bolt retracting means, a coupling member pivotally connecting said handle to said retracting means for relative pivotal movement in one direction, means adapted to cooperate with said handle to lock said retracting means upon said relative pivotal movement of said handle, and outside bolt retracting means adapted to be locked against operation through the locking of said first retracting means. 75
45. In a latch, a bolt adapted to be projected and retracted, inside bolt retracting means, a handle pivotally mounted on said means, means cooperatively related to said handle whereby the handle is adapted to be manually moved to locked and unlocked relation therewith, and outside bolt retracting means adapted to be locked against operation through the locking of said handle. 80
50. In a latch, a bolt adapted to be projected and retracted, inside bolt retracting means, an extension pivotally mounted on said means, means cooperatively related to said extension whereby the latter is adapted to be manually moved to locked and unlocked relation therewith, and outside bolt retracting means adapted to be locked against operation through the locking of said extension, said bolt in the locked relation of said extension being free to move in retracting direction through pressure applied to one end of said bolt. 85
55. In a latch, a bolt adapted to be projected and retracted, inside bolt retracting means, an extension pivotally mounted on said means, means cooperatively related to said extension whereby the latter is adapted to be manually moved to locked and unlocked relation therewith, and outside bolt retracting means adapted to be locked against operation through the locking of said extension, said bolt in the locked relation of said extension being free to move in retracting direction through pressure applied to one end of said bolt. 90

Signed at Bridgeport, in the county of Fairfield, and State of Connecticut, this 21st day of May, 1924.

RAYMOND G. MOORE.
